UNITED STATES PATENT OFFICE.

GEORGE WILLIAM CHILEN, OF LONGBEACH, CALIFORNIA.

WASHING-MACHINE.

1,090,275.

Specification of Letters Patent. Patented Mar. 17, 1914.

Application filed February 17, 1913. Serial No. 751,174.

To all whom it may concern:

Be it known that I, GEORGE W. CHILEN, a citizen of the United States, residing at Longbeach, in the county of Los Angeles and

5 State of California, have invented a new and useful Washing-Machine, of which the following is a specification.

My invention relates to improvements in washing machines, and the object of my invention is to provide a washing machine combining simplicity of construction with ease of operation and rapidity in cleansing. I attain this object by means of the mechanism illustrated in the accompanying drawings, in which—

Figure 1 is a perspective view of my machine. Fig. 2 is a vertical section. Fig. 3 is a sectional plan.

20 The same reference characters indicate the same parts in the several figures.

In the casing 1 supported by the legs 2, I form the central chamber 3 and the two end chambers 4 and 5 by means of the vertical partitions 6 and 7. In the lower portion of 25 these partitions I form the openings 8 and 9 and in the top, of the same the openings 10 and 11.

In the central chamber 3 is fitted loosely the plunger 12 which may be constructed of 30 perforated metal or a wire netting in a wooden frame, the latter being preferable, the wire netting 12 being fitted into the wooden frame 13. The cone 14 provided with the perforations 15 is secured in any 35 suitable manner to the center of the plunger 12, and the plunger rod 16 is secured in the top of the cone 14 and passes loosely up through the orifice 17 in the top 18 and is pivoted to the cross bar 19.

40 In the end chambers 5 and 4 are fitted the plungers 20 and 21 respectively having the washers 23 and 22 around their edges to make them comparatively water tight. The sockets 24 and 25 are formed on or attached 45 to these plungers, and in these sockets are secured the plunger rods 26 and 27 which pass upward through the orifices 28 and 29 in the top 18 where they are pivoted to the cross bar 19.

50 The cross bar 19 projects at both ends over the ends of the casing 1 and these ends are journaled in the bearings 30 and 31 in the arms 32 and 33. Under the bottom of the casing is journaled the crank shaft 34

having the cranks 35 and 36 on the ends 55 thereof and extending beyond the ends of the casing. These crank shafts are connected with the arms 33 and 32 respectively.

The operating lever 37 is pivoted at one end to the standard 38 on the back of the 60 casing top, and also to the cross bar 19, and the handle end extends out beyond the casing.

In operation, when the lever 37 is depressed the plungers 12, 20 and 21 are forced 65 downward, the plunger 12 compressing the clothes in the central chamber and causing the water to pass through them and rise above the netting of the plunger. At the same time the plungers 20 and 21 force the 70 water that is in the chambers 4 and 5 through the openings 8 and 9 into the chamber 3. When the plungers are raised the water in the chamber 3 is again allowed to saturate the clothes and to pass through the 75 openings 8 and 9 into the chambers 4 and 5. Should any water pass the plungers 20 and 21 it is forced into the chamber 3 through the openings 10 and 11. The water may all be drawn off through the faucet 39. 80

By a continuous upward and downward movement of the operating lever the water is forced through the clothes and rapidly cleans them.

What I claim as my invention and desire 85 Letters Patent for, is—

In a washing machine comprising a casing, a central chamber, auxiliary chambers on opposite sides of said central chamber, partitions between and having passages connecting said chambers; a plunger in the central chamber composed of a perforated base, and a conical top, a plunger rod secured to said base and slidable in said central chamber, plungers slidable in said auxiliary 90 chambers having a base and a rod, a transverse bar above the top of the casing connecting all of said plungers, a crank shaft under the casing, cranks on each end of said shaft, arms connecting said cranks with said transverse bar, and a lever pivotally secured to the top of the casing and to said transverse bar for operating said machine, in combination as described. 100

GEORGE WILLIAM CHILEN.
